UNITED STATES PATENT OFFICE.

ARTHUR O. DADY, OF NEW YORK, N. Y., ASSIGNOR TO PFANSTIEHL COMPANY, INC., OF NORTH CHICAGO, ILLINOIS, A CORPORATION OF NEW YORK.

IGNITION MECHANISM FOR INTERNAL-COMBUSTION ENGINES.

1,329,654.

Specification of Letters Patent.

Patented Feb. 3, 1920.

Application filed July 27, 1917. Serial No. 183,042.

To all whom it may concern:

Be it known that I, ARTHUR O. DADY, a citizen of the United States, residing at New York, in the county of New York and State 5 of New York, have invented a certain new and useful Improvement in Ignition Mechanism for Internal-Combustion Engines, of which the following is a full, clear, concise, and exact description, reference being had 10 to the accompanying drawings, forming a part of this specification.

My invention relates to ignition mechanism for internal combustion engines, and more particularly to ignition mechanism 15 which includes a battery, a vibrator, arranged to coöperate with the battery circuit, and a magneto, together with circuit connections whereby either the magneto or the battery together with the vibrator may be 20 employed for generating the current necessary for ignition in the engine cylinders.

The primary purpose of a system of this kind, which includes two sources of current, is to provide some means for generating an 25 efficient spark at low engine speeds or at starting of the engine. It has been the practice to provide suitable switching mechanism in connection with the ignition circuit whereby it is possible to control the ignition 30 circuit to utilize the battery upon starting of the engine or at low running speeds thereof, and to cut out the battery and utilize the magneto at higher engine speeds.

The system of my invention incorporates 35 the use of a timer which serves to determine the point in the engine cycle at which sparking occurs. When the battery is furnishing the current necessary for ignition, or, in other words, when the engine is running at 40 low speed the timer is set to its retarded position so that sparking occurs at the proper point of the engine cycle and when the magneto is employed and the engine is running at high speed the timer is set to its advanced 45 position.

It is one of the objects of the present invention to provide an improved arrangement of mechanism for simultaneously controlling the ignition circuit and for controlling the advance and retard of the timer so 50 that when the battery circuit is included in the ignition system the timer will automatically assume its retarded position and when

the battery circuit is cut out of the ignition system and the magneto current utilized to 55 furnish ignition the timer will automatically assume its advanced position.

In my co-pending application, Serial No. 183,043, filed July 27, 1917, I have disclosed mechanism for simultaneously controlling 60 the ignition circuit and timer which includes a rotary form of switching mechanism for controlling the ignition circuit. In the present system I employ a switching device arranged to control the ignition circuit upon rectilinear movement of the device, suitable connections being provided between the switching device and the timer so that both 65 may be operated in unison.

These and other objects of the present invention will be pointed out more fully in connection with the accompanying drawings wherein,

Figure 1 is a diagrammatic circuit drawing showing the ignition system of my invention;

Fig. 2 is a view showing the mechanism of my invention as it appears when in use;

Fig. 3 is an enlarged detail cross sectional view of the switching mechanism of my invention; and

Fig. 4 is an enlarged detail cross sectional view of the lower end of the switching rod shown in Fig. 3.

Similar characters of reference refer to 85 similar parts throughout the several views.

Referring first to Fig. 2, I have shown at 5 a portion of an automobile located at a point convenient to the operator, such, for example, as the instrument board, through 90 which extends a switch 6 which is provided with an operating handle 7. The back of the board carries a vibrator 8 provided with binding posts shown at 9 and 10. The binding post 9 is connected through the conductor 11 with a battery 12, the other side of which is connected through the conductor 13 with ground. The binding post 10 of the vibrator is connected through conductor 14 with binding post 15 of the switch 6. The 100 magneto is shown at 16 provided with a distributor 17, the contacts of which terminate in the binding posts 18—18 arranged to be connected with the several spark plugs of the internal combustion engine. The interrupter is shown at 19 provided with a lever 105

arm 20 in turn connected through the wire 21 with the switch 6, as will be described presently. The timer carries the terminal 22 connected through the conductor 23 with the terminal 24 mounted on the switch 6.

As most clearly illustrated in Fig. 1, the magneto comprises the horse shoe magnets 25, the pole pieces 26 and 27, a rotor 28 mounted for rotation between the pole pieces 10 and a pair of induction coils 29 and 30 mounted in inductive relation around the rotor. The winding 29 constitutes the primary winding and the winding 30 the secondary winding. The secondary winding 15 is connected through the conductor 31 with a brush 32 arranged to engage the contacts 33—33, which are connected with the spark plugs, one after another. The end of the secondary winding opposite the brush 32 20 is connected to conductor 34 in turn connected with the block 35 mounted on the timer or interrupter of the magneto. The block 35 is carried by and insulated from the plate 36 to which is also pivotally attached at 37 an interrupter lever 38 carrying a contact 39 arranged to coöperate with the contact 40 mounted on the block 35. The interrupter lever 38 is grounded, as 25 shown at 41.

30 Mounted around the interrupter lever 38 is a sleeve 42 carrying the two cams shown at 43 and 44. The sleeve 42 is rigidly connected with the lever arm 20. One end of the primary winding 29 is connected with 35 the conductor 34 and its opposite end grounded at 45.

From the construction thus far pointed out the operation of the magneto may be described. The plate 36 is connected with the rotor 28 so as to rotate therewith and the brush 32 also connected with the rotor through the gearing shown in dotted lines, whereby the brush serves to provide the necessary electrical connections to the several spark plugs. Upon rotation of the rotor and plate 36 in the direction indicated by the arrow the contacts 39 and 40 will be opened and closed alternately, due to the engagement of the lever 38 with the two cams 43 and 44, there being suitable spring mechanism employed for holding the lever 38 normally in a position where its contact 39 engages the contact 40. When the lever 38 assumes a position between the cams 43 and 44 a circuit is provided from the primary winding 29 through conductor 34, contact 40, contact 39, and interrupter lever 38 to ground 41 back to the grounded side of the primary winding. As the rotor and 50 plate 36 continue to rotate the interrupter lever 38 engages one of the cams with the result that the contacts 39 and 40 are opened so as to interrupt the flow of current through the primary winding. The sudden collapse 55 of the current in the primary winding results

in a high inductive current in the secondary winding 30, which is sufficient to produce the required spark.

Arranged to fit over the sleeve 42 is a cap 46 through which the binding post 22 extends. Attached to the inner end of the binding post 22 is a spring contact 47 arranged to rest against the block 35. The post 22 is connected through the conductor 48 with the conductor segment 49 of the switch member 6. The switch member also comprises the two stationary conductor segments 50 and 51 and the movable conductor 52. The segment 51 is connected to a plate 53 of the vibrator 8 through the conductor 14. This plate is preferably mounted on an iron core 54 carrying a winding 55, one end of which is connected with battery through conductor 11 and the other end connected with an armature 56 provided with a contact 57 arranged to coöperate with a contact 58 carried by the plate 53. A condenser circuit 59 is provided across the contacts 57 and 58 to prevent sparking across the contacts.

The movable conductor segment 52 of the switch member is movable in a longitudinal direction and is arranged to connect the conductor segments 49 and 50 and 49 and 51. The segment 50 is grounded at 60. 95 The movable segment 52 is connected by means of a wire to the timer or interrupter arm 20 so that movement of the segment 52 will cause movement of the arm 20 whereby the advance or retard of the timer may be controlled by the switch. The wire connection between the member 52 and arm 20 will be described in detail hereinafter.

Assuming that the engine is to be started, or is running at low engine speed, the member 52 is moved to the left (Fig. 1) so that it assumes the position shown in dotted lines at "Bat" whereby it connects the segments 49 and 51. The battery is then in condition to supply the current for ignition and the circuit is as follows: from battery 12 through conductor 11, through vibrator to segment 51, through segment 52, segment 49, conductor 48, terminal 22, spring contact 47, block 35, through contacts 39 and 40 to ground at 41 and back to battery. As the rotor and interrupter are rotated the contacts 39 and 40 are separated with the result that the battery current is led through conductor 34 and primary winding 29. The rapid building up and collapsing of the current in the primary winding 29, due to the vibrator, serves to induce a current in the secondary winding sufficient to provide efficient ignition. When the segment 52 is moved to the 110 position just referred to the lever 20 is moved downwardly so that the timer is retarded.

When the segment 52 takes the position "Mag" the battery circuit is cut out of the 130

system and the magneto permitted to operate and furnish the current necessary for ignition. When it is desired to stop the motor the segment 52 is moved to the position "Off" whereby it connects the segment 49 with the segment 50 and thus to ground. The primary winding is then permanently grounded and is rendered inoperative.

The detail construction of the switch member 6 and the connection between the switch and the timer are most clearly illustrated in Figs. 3 and 4. The switch member 6 comprises a metallic sleeve member 61 provided with the flanges 62 and 63 to facilitate connection of the sleeve to the instrument board of an automobile. Mounted concentric with the sleeve 61, and attached thereto in any suitable manner, is a sleeve 64 made up of insulating material. The outer end of the sleeve 64 is attached to a metallic coupling 50 which forms also a conductor segment. The coupling 50 is attached to the metallic tubing 65 which serves to cover and guide the wire 21 attached to the timer lever 20. Mounted for rectilinear movement within the sleeves 61 and 64 is a rod 66 carrying at its outer end a finger piece 7. The inner end of the rod 66 carries the conductor segment 52 which is insulated from the rod by the insulating washers, as most clearly shown in Fig. 4. The end of the rod is also provided with an aperture 68 which serves to provide means whereby the wire 21 may be attached to the rod. The conductor segment 49 is embedded in the insulator sleeve 64, as is the conductor segment 51. The rod 66 is provided with a shoulder at 69 arranged to engage a washer 70 held in place by a coiled compression spring 71 interposed between it and the sleeve 64. The arrangement of the spring mechanism just referred to is such that the rod 66 may be moved longitudinally within the sleeves without in any way compressing the spring 71 unless the rod is moved to a position whereby the segment 52 contacts with the segment 50, whereupon the spring 71 is compressed and the rod returned to the position shown in Fig. 3 as soon as the finger piece 7 is released.

Having thus described my invention, what I claim as new and desire to secure by Letters Patent of the United States is:

1. In an ignition system for internal combustion engines, the provision of a distributor, a timer, two separate sources of current, one for use at high engine speeds and the other for low engine speeds, a switch and circuit connections for rendering either one of said sources operable in the ignition system, said switch comprising a tubular casing having conductor and insulator segments disposed along its length, a switch member longitudinally movable in the casing for electrically connecting the conductor segments, and linkage connecting the switch member and the timer, whereby the latter is advanced and retarded upon operation of the switch.

2. In an ignition system for internal combustion engines, the provision of a distributor, a timer, two separate sources of current, one for use at high engine speeds and the other for low engine speeds, a switch and circuit connections for rendering either one of said sources operable in the ignition systems, said switch comprising a tubular casing having conductor and insulator segments disposed along its length, one of the conductor segments being arranged at one end of the casing for the purpose of short-circuiting one of the sources of current around the interrupter, a switch member longitudinally movable in the casing for electrically connecting the conductor segments, a spring interposed between the casing and the switch member arranged normally to prevent electrical connection between the switch member and the said short-circuiting conductor segment, and linkage connecting the switch member and the timer, whereby the latter is advanced and retarded upon operation of the switch.

In witness whereof, I hereunto subscribe my name this 23 day of July, A. D. 1917.

ARTHUR O. DADY.
